C. C. RAMSAY.
GAS PRESSURE REGULATOR.

No. 81,944.

Patented Sept. 8, 1868.

United States Patent Office.

CHARLES C. RAMSAY, OF CHICAGO, ILLINOIS.

Letters Patent No. 81,944, dated September 8, 1868.

IMPROVED GAS-PRESSURE REGULATOR.

The Schedule referred to in these Letters Patent and making part of the same.

TO ALL WHOM IT MAY CONCERN:

Be it known that I, CHARLES C. RAMSAY, of the city of Chicago, in the county of Cook, and State of Illinois, have invented certain new and useful Improvements in "Gas-Pressure Regulators;" and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

The object of my invention is to provide an apparatus, to be connected with mains and pipes, through which coal-gas or any other gaseous substances are admitted, for lighting or other purposes, said apparatus so arranged that the pressure of said gas or gaseous substances is always equalized; and the nature of the apparatus consists in the application of a surface, partition, or diaphragm, made of India rubber or other elastic substance, suitably placed in a case, through which said gas or gaseous substances pass, before they reach the burner, said diaphragm having its surface of such dimensions and capacity that, by being properly connected with the valve admitting gas or gaseous substance into said case, it will, when undue pressure is produced, carry up the valve into its seat, thus regulating the aperture, and thereby equalizing said pressure of the gas or gaseous substances all the time.

A is a metallic case, on to the top of which is screwed a large circular chamber, B, divided by India-rubber or other elastic partition or diaphragm, b. C is a valve, the stem, D, of which moves in seats d d, and the valve rests on lever E, one end of which is hinged to the case, and the other is connected by wire or rod, F, with plate f, which in its turn is connected to plate f' by pin and nut, or otherwise, the diaphragm b being between the two said plates. On the upper plate, f, rests plate g of the rod G, around which coil-spring H is wound, which spring is enclosed and compressed by sleeve K, secured to the fixture L, at any height, by set-screw M, all for the purpose of balancing the diaphragm b. N is the inlet into the case, and O is the outlet, for gas or gaseous substances, to the burners.

The apparatus may be made of any shape, and placed in any position to suit different circumstances.

The operation consists in this, that, when an undue pressure of gas or gaseous substance is exercised on the valve, and the aperture is immensurably enlarged, that pressure inflates the diaphragm, and extends and moves its centre upwards, thus causing the valve to close against the said pressure, and thereby balancing and equalizing the same, so that the device may be considered as a single balance-valve, in which, the stronger is the pressure; the deeper enters the valve into its seat.

The economy produced thus by equalization of the pressure of gas, and the cheapness of the apparatus itself, are important advantages gained.

The apparatus can be used for carburetting-devices, as well as for devices supplying gas of any kind, or any gaseous substances, to the burners.

I am well aware that the pressure-regulators have been and are in use; also, I do not claim the diaphragm b, *per se*; but

What I do claim as my invention, and desire to secure by Letters Patent, is—

The combination of chamber B, having the diaphragm b, with the spiral spring H, arranged as shown, with the valve C resting on the lever E, connected to the diaphragm by a rod, F, all arranged to operate substantially as herein set forth.

CHARLES C. RAMSAY.
